HEAD REST COVER FOR DENTAL CHAIRS

Filed March 20, 1929

FIG. 1. FIG. 2. FIG. 3.

IRVING E. ROTNER,
INVENTOR

BY *Victor J. Evans*

WITNESS:

John D. Party

ATTORNEY

UNITED STATES PATENT OFFICE

IRVING E. ROTNER, OF NEW YORK, N. Y.

HEADREST COVER FOR DENTAL CHAIRS

Application filed March 20, 1929. Serial No. 346,558.

This invention relates to improvements in head rest covers for dental chairs and the like.

The primary object of the invention resides 5 in a sanitary head rest cover which may be applied to the head rest of a dental chair and after one use of the same, it may be discarded and a clean one promptly substituted therefor to prevent the spread of scalp diseases 10 from one user to another. I am cognizant that various types of such covers have been placed upon the market but they have proven more or less inconvenient in applying and removing to and from a head rest which 15 tends to discourage extensive use and the changing of the same after each use. Furthermore, difficulty has been experienced in causing the covers to remain in a flat proper position when applied to a head rest which 20 detracts from the neatness of the chair, and greatly adds to the discomfort of the user. My invention aims to overcome these objections by providing a simple and practical 25 cover for that type of head rest now commonly used on dental chairs and the like.

Another object of the invention is the provision of a head rest cover formed of a single piece of foldable material having separate attaching pockets for the reception of the two 30 cushioned head rest members, and a seam or crease intermediate the pockets to cause the covering surfaces of the cover to assume a substantially V-shape when in an applied 35 position and which surfaces lie flat upon the head rest sections without wrinkling.

With these and other objects in view, the invention resides in certain novel construction and combination and arrangement of parts, the essential features of which are 40 hereinafter fully described, are particularly pointed out in the appended claims, and are illustrated in the accompanying drawing, in which:

Figure 1 is a perspective view of a chair 45 head rest with my invention applied thereto.

Figure 2 is a vertical sectional view therethrough.

Figure 3 is a horizontal sectional view on the line 3—3 of Figure 2.

Figure 4 is a perspective view of the cover 50 per se.

Figure 5 is an enlarged horizontal section- 55 al view on the line 5—5 of Figure 4.

Referring to the drawing by reference characters, the numeral 10 designates my 55 improved head rest cover in its entirety which is constructed of a single piece of foldable material such as linen or paper. The material is folded in a manner to provide a substantially oblong envelope open at one 60 of its longitudinal edges. The closed corners of the cover are rounded or bevelled as at 11 for a purpose to be presently described. The envelope includes a front wall 12 and a rear wall 13, which walls are fixedly connect- 65 ed together midway between their ends by transversely creasing the same together from the open longitudinal edge to the closed lon- 70 gitudinal edge as at 14, and passing stitching 15 through the four plies of folded material 70 to provide a seam as clearly shown in Figure 5 of the drawing. The envelope cover is therefore divided centrally into two separate 75 attaching pockets 16, and the rear walls of these pockets are provided with slots 17 which extend inwardly from the open edge. These slots are substantially midway between the closed sides of the respective pockets.

In the drawings, I have illustrated my 80 sanitary cover in use upon a dental chair 80 head rest 18 which includes the usual shank 19 adapted to be inserted into the socket pro- 85 vided on the chair. The stem supports cross arms 20 on which the two spaced cushioned head rest members 21 are adjustably mount- 85 ed, the backs of which are provided with at- 90 taching arms 22. In applying a cover as herein described to the head rest 18, the walls of the pockets 16 are spread apart and the open sides of the pockets brought down over the 90

respective rest members 21 until the closed ends of the slots 17 engage the arms 22 of the said members. The weight of the crease or seam 14 causes the cover to break downward between the head rest members whereby the 5 cover assumes a substantial V-shape to comfortably receive the head of a user in the crotch thereof. The pockets serve to properly center the cover upon the head rest and retain the same in a flat condition thereon 10 against the natural tendencies of a person in the shifting of their head from one position to another. From the foregoing description, it will be seen that the cover is convenient to 15 apply and retain in position, and can be readily removed by pulling thereon.

By rounding or beveling the closed corners of the head rest, the same adapts itself to the curvature of the head rest members to 20 produce a form fitting appearance.

In instances where the cover is constructed of linen or other fabric, the same may be laundered after each use, and if made of paper or other inexpensive material, the same 25 may be thrown away after each use. By this practice, a clean cover can be used for each individual user of the chair which will prove highly sanitary as the spread of scalp and other skin diseases may be prevented.

30 While I have described what I deem to be the most desirable embodiment of my invention, it is obvious that many of the details may be varied without in any way departing from the spirit of my invention, and I therefore do not limit myself to the exact details 35 of construction herein set forth nor to anything than the whole of my invention limited only by the appended claims.

What is claimed as new is:—

40 1. A head rest cover for dental chairs and the like comprising an envelope of flexible material open along one of its edges, and a transverse crease dividing the interior of said envelope into two separate pockets, the 45 rear walls of said pockets being provided with slots extending inwardly from their open edges for accommodating the supports of the cushion head rest members.

50 2. A head rest cover comprising an envelope of flexible material open along one of its edges, the walls of said envelope being creased and secured together in a transverse direction midway between their ends to provide a seam and a pair of separate pockets 55 within said envelope, the rear walls of said pockets being provided with slots extending inwardly from their open edges for accommodating the supports of the two separate head rest members.

60 3. A head rest cover for dental chairs and the like, including an elongate envelope of flexible material open along one of its longer edges, and having a transverse seam incorporated in said envelope extending trans- 65 versely thereof and located substantially mid-

way between its ends, thereby to provide a distinctly localized line of fold at said seam and to establish a plurality of individual pockets one on each side of such line of fold, each of said pockets having a wall provided with an opening for coaction with structural elements of the head rest to assist in securing the cover thereon.

In testimony whereof I hereby affix my signature.

IRVING E. ROTNER.
